TYPEWRITING AND LIKE MACHINES

Russell G. Thompson, West Hartford, Conn., assignor to Remington Rand Inc., Buffalo, N. Y., a corporation of Delaware

Application July 19, 1939, Serial No. 285,369

3 Claims. (Cl. 197—73)

My invention relates to typewriting and like machines and is directed more particularly to providing substantially the same coefficient of expansion between two connected, relatively movable parts of the machine when one of said parts is made of an aluminum alloy and the other of said parts is made of steel.

Aluminum alloy has a coefficient of expansion of about twice that of ordinary steel. It has been found that when two relatively movable, pivotally united, parts of a typewriting machine—one made of an aluminum alloy and the other of ordinary steel—are employed, a setting of the pivotal connection to function freely at, say, room temperature will result in an undue binding of the pivotal connection when the machine is subjected to a lower temperature, due to different coefficients of expansion of the two connected parts.

One of the main objects of the present invention, generally stated, is to overcome this difficulty and provide two such parts as those indicated above which have substantially the same coefficients of expansion.

To the above and other ends which will hereinafter appear, my invention consists of the features of construction, arrangements of parts and combinations of devices hereinafter described and particularly pointed out in the appended claims.

In the accompanying drawings, wherein like reference characters indicate corresponding parts in the different views:

Fig. 1 is a fragmentary, vertical, central, fore and aft sectional view showing a portion of a No. 10 Remington Noiseless machine embodying my invention; the section being taken on the line 1—1 of Fig. 3 and looking in the direction of the arrows at said line.

Fig. 2 is a side view, with parts in section, of a portion of the center tie connections of said machine.

Fig. 3 is a top plan view of the construction shown in Fig. 1 with parts sectioned away.

Fig. 4 is a detail sectional view taken on the line 4—4 of Fig. 3 and looking in the direction of the arrows at said line.

Fig. 5 is a detail, sectional view taken on the line 5—5 of Fig. 3 and looking in the direction of the arrows at said line.

Fig. 6 is an enlarged, detail sectional view taken on the line 6—6 of Fig. 3 and looking in the direction of the arrows at said line.

Fig. 7 is an enlarged, detail sectional view tak-

en on the line 7—7 of Fig. 3 and looking in the direction of the arrows at said line.

I have shown my invention embodied in the present instance in a No. 10 Remington Noiseless machine. It should be understood, however, that the invention is not restricted to such embodiment but may be employed in various forms of typewriting and like machines wherever found available.

In the accompanying drawings I have shown only so much of the No. 10 Remington Noiseless machine as may be necessary to arrive at an understanding of my invention in its embodiment therein.

The machine shown in the present instance includes a carriage 8 carrying a platen 9 and having a guide rail 10 with oppositely disposed grooved ways therein. These ways receive anti-friction crossed bearing rollers 11 which also are received in oppositely grooved bearings in a supporting member 12 mounted for case shifting movement. The carriage also coacts in the usual manner by means not shown, with an upstanding part 13 of a supporting member 14; the part 13 being located in the center of the machine in the rear of the printing point to resist the pressure of the type bars against the platen.

The carriage support 12 has attached thereto two depending brackets 15, one near each side of the machine. To the lower end of each bracket is attached a coiled expansion spring 16 to partly counter-balance the weight of the carriage and the support 12 therefor. The upper end of each spring 16 is connected to a nut 17 threaded on a headed screw 18 received in an unthreaded opening in the support 14 and by which the tension of each spring 16 may be varied.

Two upstanding lugs 19 are formed integral with the supporting member 14 and each lug is tapped transversely to receive a hardened pivot screw 20. The pointed bearing end of the left hand pivot screw is received in a bearing opening in a hardened steel plate or arm 21. Said arm is adjustably secured to a second hardened steel plate or arm 22 which is fixed to a rock shaft 23. Preferably the left hand end portion of said shaft is slabbed off at 24 and is received in a corresponding opening in the arm 22 so that said arm and shaft are fixedly united to turn together. The arm 22 may be brazed to the shaft 23 as indicated at 25.

The extreme left-hand end 26 of the shaft 23, however, is cylindrical in form and is received in a corresponding bearing or depression in the

plate or arm 21. Said cylindrical end 26 of the shaft and the bearing in the plate 21 in which it is received are concentric with the associated pivot screw 20 so that the arm 21 may receive an adjustment relatively to the plate 22 around the axis of the companion pivot screw 20. The means for effecting such adjustment of the arm 21, and for holding it in its adjusted position relatively to the arm 22, comprises an eccentric 27 that is received in an elongated opening 28 in the arm 21 and has a hexagonal head 29 by which the eccentric may be turned around a headed clamping screw 30 that is received in a tapped opening in the arm 22. Additional headed clamping screws 31 and 32 pass through elongated openings 33 and 34 respectively in the arm 21 and are received in tapped openings in the arm 22 to retain the arm 21 in its adjusted position on the arm 22. It will be understood that due to the support of the arm 21 on the cylindrical end 26 of the shaft, and to the disposition of the slots 28, 33 and 34, a turning of the eccentric 27 will effect a turning adjustment of the arm 21 around the pivotal axis of the companion pivot screw 20 as a center when the clamping screws have been loosened.

The arm 21 is provided with an off-set ear 21^a that is tapped to receive a screw stop 21^b which at its lower end coats with a companion stop face 21^c on the support 14. These stops coat to arrest the arms 21 and 22 and the shaft 23 in the movement thereof in one direction.

The other end of the shaft 23 has a hardened steel arm 35 fixedly secured thereto in the same manner as the arm 22. From a consideration of Fig. 5 it will be seen that a companion hardened steel arm 36 has a bearing opening therein to receive the companion pivot screw 20, and that said arm 36 is adjustably secured to the arm 35 with the aid of two headed clamping screws 37 which extend through substantially horizontally disposed elongated slots 38 in the arm 36 and are received in tapped openings in the arm 35. Adjacent slots 39 are provided in the upper edges of the arms 35 and 36 to receive a screw driver. A twisting movement of the screw driver effects a slight horizontal adjustment of the arm 36 fore and aft of the machine relative to the arm 35 when the screws 37 are loosened. This adjustment of the shaft 23 brings the carriage support 12 and the front face of the platen into a trued position at the right and left hand ends thereof and affords a proper alignment of the carriage.

It will be seen that the rear end of each of the arms 22 and 35 is pivotally connected at 40 to a depending lug 41 on the carriage support 12, whereas the forward end of the arm 21 is pivoted, at 42, to a depending link 43. Said link 43 may be connected in the usual manner (not shown) with two case shift keys, so that an actuation of each of said keys will rock the shaft 23 and effect a shifting movement of the carriage to upper case position.

The supporting member 14 may be supported in the usual manner for bodily adjustment fore and aft of the machine together with the carriage supported thereby. Thus, said member 14 has a sliding adjustment fore and aft of the machine on an underlying fixed support 44, whereas a fixed member 45 overlies a forward extension 46 on the member 14. The above described adjustment of the member 14 is effected with the aid of a link 47 located centrally of the machine and pivoted at 48 to said member.

The forward end of the link carries the usual threaded member 49 that cooperates with an interiorly threaded member 50 connected to a finger piece 51 by which it may be turned in one direction to effect a forward adjustment of the member 14 and the parts carried thereby. A turning movement of the finger piece in the opposite direction results in adjusting the member 14 and the parts carried thereby in the opposite direction.

The construction thus far described constitutes what is generally termed the "center tie" mechanism and is substantially such a construction as has heretofore been employed in the No. 10 Remington Noiseless machine.

In accordance with the present invention the support 14 is a die casting made from an aluminum alloy. In practice I have found that an aluminum alloy comprising 83% aluminum and 12% silicon by weight gives very good results although an alloy comprising 90% aluminum, 5% copper and 5% silicon by weight may be employed. The coefficient of expansion of these and other aluminum alloys is about twice that of ordinary steel. Thus the aluminum die casting support 14 has a coefficient of expansion of .000022 per degree C., whereas ordinary cold rolled steel has a coefficient of expansion of .000011 per degree C.

For various reasons, including undue wear thereon, it has been found to be undesirable to make the rock shaft of an aluminum alloy so as to have the same coefficient of expansion as the aluminum die casting 14. On the other hand it has been demonstrated in practice that when the rock shaft 23 is made of ordinary steel serious difficulties are encountered due to the differences in the coefficients of expansion of said shaft and the aluminum die casting 14. Thus, when the shaft was set to be free for movement on its pivotal supports at ordinary room temperature and the typewriter was placed in operation in a lower temperature the aluminum contracted more than the steel with the result that the shaft unduly bound at its bearings rendering a readjustment necessary or desirable. It is one of the main objects of my invention to overcome this serious difficulty. I have found that "Allegheny Steel No. 88" has the same coefficient of expansion as aluminum. This steel is non-magnetic and mildly corrosion-resistant and contains 12 to 14% nickel, 5 to 7% manganese and less than 1% chromium. As far as I have been able to discover it is the only steel that has the same, or substantially the same, coefficient of expansion as aluminum alloy. In the present construction I make the rock shaft 23 of said "Allegheny Steel No. 88" and thus provide the same coefficient of expansion of the shaft 23 and the aluminum die casting 14, thereby overcoming the difficulties pointed out above.

While I have specifically described the embodiment of my invention in a No. 10 Remington Noiseless machine and to the rock shaft 23 and member 14 thereof, obviously the invention is applicable to any typewriting or like machine in which two relatively movable pivotally united parts are employed and in which one of said parts is made of an aluminum alloy and the other is made of steel and it is desirable to have substantially the same coefficient of expansion in both of said parts.

Various changes may be made in the construction without departing from my invention as it is defined in the accompanying claims.

What I claim as new and desire to secure by Letters Patent is:

1. In a typewriting machine the combination of two relatively movable interfitting parts, one of said parts being made of an alloy comprising 88 to 90% aluminum and the other part being made of steel having substantially the same coefficient of expansion as said aluminum alloy part, said steel comprising 12 to 14% nickel, 5 to 7% manganese and less than 1% chromium.
2. In a typewriting machine, the combination of a support of an alloy containing at least 88% of aluminum and having spaced bearing members, and a steel rock shaft fitting longitudinally between said bearing members, said rock shaft being made of steel having the same coefficient

5 of expansion as the aluminum alloy of said support, and comprising 12 to 14% nickel, 5 to 7% manganese and less than 1% chromium.

3. In a case shift mechanism for typewriting machines, the combination of an aluminum alloy supporting member, hardened steel pivot bearings fixedly secured to said supporting member, and a hardened steel rock shaft arranged to fit snugly between said pivot bearings, said rock shaft being made of steel having the same coefficient of expansion as the aluminum alloy of said support to maintain said snug fit with the pivot bearings regardless of ambient temperature changes.

RUSSELL G. THOMPSON.
